UNITED STATES PATENT OFFICE.

SOLOMON M. CUTTER, OF WETHERSFIELD, CONNECTICUT, ASSIGNOR TO THE CAPEWELL HORSE NAIL COMPANY, OF HARTFORD, CONNECTICUT, A CORPORATION OF CONNECTICUT.

METHOD OF CLEANING ROD.

1,142,499.

Specification of Letters Patent.

Patented June 8, 1915.

Application filed February 26, 1914. Serial No. 821,142.

To all whom it may concern:

Be it known that I, SOLOMON M. CUTTER, a citizen of the United States, residing at Wethersfield, in the county of Hartford and State of Connecticut, have invented a new and useful Improvement in Methods of Cleaning Rod, of which the following is a specification.

This invention relates to a method of 10 cleaning wire or continuous lengths of rod, such stock for instance as the soft steel rod which is used for manufacturing horseshoe nails. In the manufacture of horseshoe nails continuous lengths of rod of rectangular cross section are first cleaned of scale and the like imperfections and then passed through draw dies to give the stock accurate size before it is fed to the nail making machines. In order to prepare such stock 15 it has been customary to bend the rod back and forth by suitable mechanism so as to break off the hard scale on the exterior, and then to pass the rod through a pickling bath and baking oven so that the rod will 20 be smooth and clean when it is passed to the drawing dies.

The object of this invention is to provide a method by means of which continuous 25 lengths of flexible rod may be very rapidly cleaned in an economical and efficient way without necessitating the use of bending and straightening mechanism and pickling and baking apparatus thereby effecting a considerable saving in the cost of cleaning 30 the rod.

Figure 1 of the accompanying drawings shows a side elevation of an apparatus which may be employed in the practice of 35 this invention. Fig. 2 shows a plan of the apparatus shown in Fig. 1. Fig. 3 shows one way of arranging a blast nozzle and the rod to be cleaned. Fig. 4 shows another way of arranging the rod and the blast nozzle.

In carrying out this invention the rod to 40 be cleaned is wound so that it will in feeding travel back and forth around two reels, that is, it is passed from the first reel around the second, back to the first, around the first to the second, around the second and 45 back to the first a number of times. In the drawings the rod is shown as wound so that there are four sections of the same length of rod passing side by side over the top and under the bottom from reel to reel. These 50 sections of the rod may, in carrying out the

process, be arranged in a horizontal plane spaced a little distance apart as shown in Fig. 3, or they may be stepped as shown in Fig. 4.

In the apparatus illustrated the upper 55 sections of the rod are shown as passing through a chamber 5 and the lower sections as passing through a chamber 6. In the upper chamber is a nozzle 7 directed obliquely toward the underside of the sections of the rod as they travel through that chamber, and in the lower chamber is a nozzle 8 directed obliquely toward the underside of the sections of rod as they travel through that chamber. These nozzles are connected 60 with a supply pipe 9 which leads from a blast apparatus for blowing, by air or steam, sand or small metallic particles through the nozzles against the surfaces of the rod as the sections pass through the chambers. The 65 tops of the chambers are connected with an exhaust pipe 10. In practising this invention it is not necessary to pass the rod through these chambers, but as a matter of convenience, neatness and efficiency it is desirable. Sand or broken particles of steel 70 or the like hard abrading substances are blown very forcibly out of the nozzles against the rod as it travels from one reel to the other. As the nozzles are directed 75 diagonally toward the rod, the bottom side and one edge of the several sections of the single continuous length of rod are thoroughly cleaned by the blast when passing through the upper chamber, and of course 80 as the rod is turned over when it passes from the second reel back to the first, what was the top and the other edge of each section are thoroughly cleaned by the blast when 85 passing through the second chamber. In this manner with two nozzles a multiple 90 number of sections of the same rod are subjected to the same blast and each part of the rod is subjected to the blast as many 95 times as there are sections passing back and forth, for each time every part passes through a chamber it is subjected to the action of the blast. As a result of this the rod may be caused to travel very rapidly, 100 as fast as two hundred feet a minute if desired, and yet it will be as thoroughly scaled, cleaned and polished and put in as suitable condition to be passed immediately to the drawing dies as it was previously 105 when subjected to bending and 110

straightening mechanism and pickling and baking apparatus. Not only can the rod be rapidly and efficiently cleaned, but the apparatus is economical as the desired result can be attained, without pickling bath or baking oven, by the use of a comparatively small amount of air or steam, thus permitting the use of a relatively cheap blast apparatus.

10 The invention may, of course, be carried out by subjecting the rod to a blast or blasts of abrasive material and not returning the rod for further treatment.

The invention claimed is:

15 1. The method of cleaning rod which consists in passing a single length back and forth so as to cause a plural number of sections of the same rod to travel parallel with each other and subjecting the several 20 sections of the same rod which travel parallel with each other to a blast containing granular material whereby every particle of the rod is subjected to the blast as many 25 times as there are sections traveling parallel with each other.

2. The method of cleaning a continuous length of rod which consists in passing the rod back and forth so as to cause a number of different sections of the same rod to travel 30 parallel with each other, and subjecting one side and one edge of the parallel rod sections to a blast containing granular material and then subjecting the other side and other edge of the parallel rod sections to a blast containing granular material.

3. The method of cleaning rod which con-

sists in passing the rod back and forth so as to cause several sections of the same rod to travel parallel with each other and directing a blast diagonally toward the sections 40 of rod, whereby one surface and one edge of each section of the rod are abraded by the blast a number of times equal to the number of sections which are traveling parallel with each other.

45

4. The method of cleaning rod which consists in passing the rod back and forth and directing a blast containing abrading material diagonally at several sections of the rod whereby at the same time one side and 50 one edge of each section are subjected to the action of the blast.

55

5. The method of cleaning rod which consists in passing a continuous length of rod back and forth about reels and subjecting 60 the under surface and one edge at one plane to a blast containing abrasive material, and subjecting the under surface and the other edge in another plane to a blast containing abrasive material whereby all the surfaces 65 of the rod are subjected to the action of the blast the same number of times that the rod is passed back and forth about the reels.

6. The method of cleaning rod which consists in simultaneously subjecting a plural 65 number of sections of the same rod to a blast containing abrasive material.
